PROCESS FOR TREATING HYDROCARBON OIL

Carbon P. Dubbs, Wilmette, Ill., assignor to The Universal Oil Products Company, Chicago, Ill., a corporation of South Dakota

Application February 12, 1923, Serial No. 618,457
Renewed May 10, 1933

4 Claims. (Cl. 196—48)

This invention relates to improvements in a process for converting petroleum hydrocarbons, and refers more particularly to the pressure distillation of petroleum oils to extract therefrom 5 the lighter oil constituents producing distillates similar to gasoline.

Among the salient objects of the invention are to provide a process in which oil is treated under pressure and the lighter hydrocarbons separated 10 therefrom in the form of pressure distillate. Simultaneously with this processing of the hydrocarbon, there is introduced to the system, a second charging stock which is separately treated, the heat of the initial system being utilized to preheat the secondary charging stock, whereby a considerable economy of fuel is effected; to provide a process in which the distillates from the separate charging stocks are separately collected, and one in which an accurate 15 temperature control may be kept upon the different stages of the two separate systems; to provide an improved type of apparatus for carrying out this process.

The single figure is a diagrammatic side elevational view of an apparatus suitable for practicing the process. Referring to the drawing, a charging stock is introduced from any convenient source through the line 1 and is charged by the pump 2 through the line 3 controlled by the 20 valve 4 to the heating coils 5 positioned in the furnace 6. After circulation through the coils, the oil is raised to a conversion temperature and is passed thence through the transfer line 7 regulated by the valve 8 to the expansion chamber 9. This expansion chamber is equipped with try-cocks 10 for ascertaining the liquid level in the chamber and residual drawoff lines 11 positioned at different heights on the chamber for withdrawing the residuum and unvaporized products 25 from the system.

Valves 12 are interposed in the separate residual lines. The vapors evolved in the chamber pass off through the line 13 controlled by the valve 14 and are directed to a dephlegmator 15 through which they rise in a circuitous travel caused by the positioning of perforated plates in the column. The dephlegmated vapors pass off from the top of the refluxing column through the line 16 regulated by the valve 17 to a heat 30 interchanger comprising an upper header 18 and a lower header 19 connected by tubes 20 interposed between the two headers. About these tubes is a chamber enclosed by a casing 21 through which a cooling medium is circulated as 35 hereinafter explained. The vapors after pass-

ing through this heat interchanger are drawn off through the line 22 controlled by the valve 23 and after passing through the condenser coil 24, they are collected as liquid distillate in the receiving tank 25.

The receiving tank is equipped with a pressure relief valve 26, pressure gauge 27, a liquid level gauge 28 and a liquid drawoff line 29 controlled by a valve 30. The liquid distillate collected in the receiving tank 25 may be drawn off through the pipe 31 in which is interposed the valve 32, this line communicating with the suction side of the pump 33. By means of this pump the distillate is recycled through the line 34 regulated by the valve 35 and charged into the top of the 15 dephlegmating column 15 through the spray pipe 36.

This distillate with what reflux condensate may be separated from the vapors due to the cooling of the air about the column, is collected 20 in the lower leg of the dephlegmator and may be drawn off through the pipe 37 regulated by the valve 38 and recycled with the charging stock through the line 3 to the heating coils, or portions of it may be removed from the system 25 through the line 39 controlled by the valve 40. This removal from the system is only necessary should the combined distillate and reflux condensate become excessive relative the amount of 30 charging stock introduced to the system.

The process explained, is the initial or primary system in which the major portion of the oil is treated. The secondary system is dependent upon the initial system for its existence, and utilizes the excess heat of the initial system.

Explaining now the functioning of the secondary system, the oil is charged from any convenient source through the line 41 and is introduced by means of the pump 42 into the casing 43 surrounding the tubes 44 of a second heat inter- 40 changer. The medium circulating through these tubes will be obvious on further explanation of the apparatus.

The oil is withdrawn from the casing 43 and passes through the pipe 45 controlled by the valve 46 to the circulating space enclosed by the casing 21 about the tubes 20. In this primary heat interchanger, the tubes 20 contain the heated oil vapors and therefore serve to transfer considerable quantities of heat to the oil circulating thereabout. After being preheated in this manner, the oil is withdrawn through the line 47, regulated by the valve 48 and is passed through the coils 49 positioned in the flue 50 of the furnace. Here, the oil acquires further heat from the par- 50 55

tially expended combustion gases passing from the bottom portion of the heating chamber of the furnace.

After passing through the coils 49 the oil has received sufficient heat to raise it to a conversion temperature and in this condition it is directed through the line 51 and may be introduced into the fractionating column 52 through either of the different vertically spaced pipes 53, 54 or 55 controlled by valves 56, 57 and 58 respectively. The pipes 53, 54 and 55 terminate in perforated sprays whereby the fluid oil constituents are introduced to the fractionating column in a finely divided condition. Perforated pans are also positioned in the column to further disseminate the fluid oil constituents in order that they may be more completely treated by the returned distillate produced by condensation of the evolved vapors. The liquid oil constituents are withdrawn from the bottom of the column through the line 59 regulated by the valve 60, and the vaporous portions pass off from the top of the column through the line 61 controlled by the valve 62. The line 61 communicates with the upper header 63 of the secondary heat interchanger to which the secondary charging stock is introduced. From the header 63 the vapors pass down through the tubes 64 to a lower header 64, thence through the line 65 regulated by the valve 66 to a condenser coil 67 and finally collected as liquid distillate in the receiving tank 68. This receiving tank is equipped with a pressure relief valve 69, a pressure gauge 70, a liquid level gauge 71 and a liquid drawoff line 72 controlled by the valve 73. A secondary drawoff line 74 connected to the pump 75 furnishes a means for recycling this secondary distillate back through the line 76, regulated by the valve 77 to the top of the fractionating column 52 where it is introduced in a finely divided condition by the circular spray 78.

The liquid products removed from the bottom of the fractionating column may be withdrawn from the system, or directed through the pipe 79 regulated by the valve 80 to the charging line 1 of the primary or initial cracking system.

By utilizing the heat of the system in this manner, practically all of the heat generated in the system is utilized in converting the oil. Also, an accurate regulation of the temperatures in the separate stages may be obtained, and a uniform distillate produced with little loss due to excessive temperatures in different portions of the system.

The secondary charging stock may be crude oil which is to be topped or it may be distillates obtained by pressure distillation of oils.

It is obvious of course, that the less refractory oil can be converted in the secondary system, as the temperatures are somewhat lower than those obtained in the initial or primary stages.

By treating gas oil of approximately 32° Baumé in the initial or primary system under pressures ranging from 50 to 200 pounds and temperatures 65 ranging from 700° to 900° F., a high quality pressure distillate comprising substantially 50% to 60% of the charging stock will be obtained of from 48° to 52° Baumé gravity, while in the secondary system a crude oil may be successfully topped to produce 20% to 30% of high boiling point distillates.

I claim as my invention:

1. A combined cracking and topping process for the continuous treatment of charging oil and crude oil, the charging oil being derived from a

source other than the crude oil, which comprises passing charging oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, subjecting the vapors uncondensed in said dephlegmating zone to

5

final condensation, simultaneously with the foregoing cracking operation heating a continuously advancing stream of the crude oil to the distillation temperature of lighter fractions thereof and utilizing in such heating waste heat of the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without passage through said dephlegmating and separating zones, to said heating zone in admixture with the charging oil.

10

2. A combined cracking and topping process for the continuous treatment of charging oil and crude oil, the charging oil being derived from a source other than the crude oil, which comprises passing charging oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, subjecting the vapors uncondensed in said dephlegmating zone to final

20

condensation, simultaneously with the foregoing cracking operation heating a continuously advancing stream of the crude oil to the distillation temperature of lighter fractions thereof and assisting the heating of the crude oil by passing the

25

same in heat exchange relation with vapors formed in the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without

30

passage through said dephlegmating and separating zones, to said heating zone to be raised to cracking temperature therein in admixture with the charging oil.

35

3. A combined cracking and topping process which comprises passing hydrocarbon oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, subjecting the vapors uncondensed in said dephlegmating zone to final condensation, simultaneously with the foregoing cracking operation heating a continuously advancing stream of crude oil to the distillation temperature of the lighter fractions thereof and utilizing in such heating waste

40

heat of the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without passage through said dephlegmating and separating zones, to said heating zone to be raised to cracking temperature therein in admixture with the charging oil.

45

4. A combined cracking and topping process which comprises passing hydrocarbon oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, subjecting the vapors uncondensed in said dephlegmating zone to final condensation, simultaneously with the foregoing cracking operation heating a continuously advancing stream of crude oil to the distillation temperature of the lighter fractions thereof and utilizing in such heating waste

50

heat of the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without

55

passage through said dephlegmating and separating zones, to said heating zone to be raised to cracking temperature therein in admixture with the charging oil.

60

5. A combined cracking and topping process which comprises passing hydrocarbon oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, subjecting the vapors uncondensed in said dephlegmating zone to final condensation, simultaneously with the foregoing cracking operation heating a continuously advancing stream of crude oil to the distillation temperature of the lighter fractions thereof and utilizing in such heating waste

65

heat of the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without

70

- charging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without passage through said dephlegmating and separating zones, to said heating zone to be raised to cracking temperature therein.
4. A combined cracking and topping process which comprises passing hydrocarbon oil in a restricted stream through a heating zone and heating the same therein to cracking temperature under pressure, introducing the heated oil to a vapor separating zone and effecting a separation of vapors from unvaporized oil therein, passing the vapors to a dephlegmating zone and condensing insufficiently cracked fractions therein, sub-
- jecting the vapors uncondensed in said dephlegmating zone to final condensation, simultaneously with the foregoing cracking operation heating a continuously advancing stream of crude oil to the distillation temperature of the lighter fractions thereof and assisting the heating of the crude oil by passing the same in heat exchange relation with vapors formed in the aforesaid cracking operation, discharging the heated stream of crude oil into a fractionating zone maintained at a temperature adequate to permit said lighter fractions of the crude oil to go off as vapor, removing and condensing said lighter fractions, supplying heavier fractions of the crude oil separated in said fractionating zone, in admixture with reflux condensate from the dephlegmating zone and without passage through said dephlegmating and separating zones, to said heating zone to be raised to cracking temperature therein.
